(57) **CLAIM**

The ornamental design for a bicycle support, as shown.

DESCRIPTION

FIG. 1 is a top front right-side perspective view of a design for a bicycle support.

FIG. 2 is a front view of the design for the bicycle support.

FIG. 3 is a rear view of the design for the bicycle support.

FIG. 4 is a left-side view of the design for the bicycle support.

FIG. 5 is a right-side view of the design for the bicycle support.

FIG. 6 is a top view of the design for the bicycle support.

FIG. 7 is a bottom view of the design for a bicycle support.

FIG. 8 is a left-side view of the design for a bicycle support (alternative position 1); and,

FIG. 9 is a left-side view of the design for a bicycle support (alternative position 2).

The bicycle support is shown with a symbolic break in its length. The breakaway symbols and any portions of the bicycle support between the breakaway symbols do not form part of the claimed design.

1 Claim, 7 Drawing Sheets
